Primary Examiner — Jennifer Rivard(74) *Attorney, Agent, or Firm* — Wang Law Firm, Inc.; Li K. Wang; Stephen Hsu(57) **CLAIM**

The ornamental design for a photocuring machine for nail painting, as shown and described.

DESCRIPTION

FIG. 1 is a perspective view of a photocuring machine for nail painting showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

The broken lines illustrate portions of the photocuring machine for nail painting and form no part of the claimed design.
